UNITED STATES PATENT OFFICE.

TITUS ANDREW BEECHER, OF TAFT, CALIFORNIA.

METHOD FOR LOCATING THE PLACE OF A LIQUID STRATUM IN A WELL.

1,090,674.

Specification of Letters Patent. Patented Mar. 17, 1914.

Application filed December 13, 1912. Serial No. 736,519.

To all whom it may concern:

Be it known that I, TITUS A. BEECHER, a citizen of the United States, and a resident of Taft, in the county of Kern and State of California, have invented a new and Improved Method for Locating the Place of a Liquid Stratum in a Well, of which the following is a full, clear, and exact description.

10 This method has for its object the location of the liquids in the ground when drilling a well or in a drilled well.

15 To carry out the above stated object, I employ proper coloring matter diffused in a predetermined place in the well, then displacing the colored liquid from the well, and then getting samples of liquid from different depths in the well and ascertaining if the samples contain any of the coloring matter diffused.

20 It is a well known fact in the oil fields that the water contained in strata above the layers containing the oil must be positively shut off from access to the well to make this well exploitable for the oil. The presence of water in the oil degrades the quality of the oil extracted from it, and, due to the existence of gases, the oil is emulsified in the water and expensive methods are necessary 25 for the separation of the oil from the water. But not only is the presence of water dangerous to this particular well in which the water stratum is leaking but it is generally drowning the oil out from the strata intersected by this particular well, and consequently it is injurious to the entire oil field. There are many methods for preventing 30 leakage of water from upper layers into the oil strata, the most commonly employed being cementation of the foot of casing passed below the water layers and resting above the oil strata. But there is no method for positive assurance that the cementation is perfect and no leak between the shoe casing and 35 the ground exists. It must also be remarked that in well drilling the boring master's journal or diary will generally give the depth of stratum from the surface and the thickness of the same, but anybody acquainted with well boring knows that is 40 only close approximation. Where few strata are intersected, as the general practice is, without placing a casing for each intersected stratum containing liquid (which 45 would be expensive and would reduce the diameter of the well so that it would become

unexploitable), it is impossible to say what that stratum contains, as there is generally a liquid already in the well.

5 In wells where oil strata are flooded by water no oil can be extracted until the water is shut off from same. It is not known where the water enters into the well and in what particular places, but the importance of shutting off the water from oil strata is 60 so great to the oil fields that States where oil fields exist have enacted laws imposing a heavy penalty for allowing water to enter oil strata.

10 It is easily seen that before the water can be shut off it must be definitely known whence this water comes, and to determine exactly the location of the stratum that supplies the water, I have designed a method by means of which the depth at which a 75 liquid enters into the well may be positively established. Also when a liquid stratum is cemented or plugged in a well by the same method it may be ascertained as to the condition of the plug of cementation, that is, 80 if a leak exists or not. While my method is primarily designed for the purpose of shutting off the water strata from the oil layers, the same method may be used for shutting off liquid strata of the upper 85 grounds from liquid strata lying in the lower grounds, or for separating mineral layers of water from ordinary water, etc.

15 Reference is to be had to the accompanying drawings forming a part of this specification, in which similar characters of reference indicate corresponding parts in all the views, and in which—

20 Figure 1 is a section through a drilled well showing the different strata and illustrating my method; Fig. 2 is a similar section through a well illustrating a modification of my method; Fig. 3 shows a leak in a casing of the well; and Fig. 4 is a partial sectional view of a container for coloring matter.

25 Referring to Fig. 1 the well is shown as intersecting layers supplying water and oil. No definite information can be gotten on the surface of the well as to where the water comes from into the well as cementation of the shoe casing 10 was made after the casing 11 was forced below the last water stratum. The fact that the oil stratum 13 was intersected was established, but this did not prevent the continuation of the boring 30 through a new stratum 14 and even farther 35 the boring was continued. When the bor-

105

110

ing was stopped, oil was present in the well and no indications of water had been found. A casing 15 was then lowered into the well provided at the lower end with a strainer 16 projecting below the shoe casing 10 so that while preventing the flow of sand into the casing 15 it admitted the liquid from the strata. After a certain length of time exploitation of the well water was detected in the same. Where the water came from it was impossible to tell. It is possible that originally the hydrocarbon gas in the oil stratum 13 produced a sufficient pressure preventing the water from the strata 14 from entering the well until a certain amount of oil was discharged from the well and the pressure thereby was reduced, thus allowing the water to enter the well. It is also possible that a leak originated below the shoe casing 10, or may be the casing 11 itself began to leak. To determine this I take a container A preferably of the form shown in Fig. 4 and made of sheet metal sufficiently strong and perforated, and into which preferably solid coloring matter is placed. The container is then attached by means of a suspension from any boring implement by means of which it is lowered into the well.

30 Since the liquid could exist only in a part, either near the shoe or below the shoe, as it must pass through the strainer, the container A with the coloring matter is lowered into the well and reciprocated between the shoe 10 and the bottom of the well. The coloring matter is washed out through the perforations provided in the container A, and diffused in the space between the shoe 10 and the bottom of the well. The specific 40 gravity of the coloring matter being slightly greater than the water it has a tendency to settle in the bottom of the well. The formation of the bottom and between the strata containing the liquids may be, as is general in wells of shale, slate or limestone, and not supposed to contain any liquid. After a certain time of agitation of the container A to allow the coloring matter within to dissolve in the place between the shoe 10 and 50 the bottom, the container is withdrawn.

55 As shown in Fig. 1, the strata 13 and 14 supply liquid into the casing 15, and by bailing or pumping out from the top, that is, from the natural level of the well these two strata will supply the liquid to maintain the natural level in the wells. In consequence of this flow from the strata 13 and 14, the coloring matter in suspension will be carried up. This discharged liquid can then be 60 analyzed, as described and claimed in my pending application. The coloring matter below the stratum 14 will remain in suspension and will not be carried away by the flow from the strata as it lies below this particular flow. When the liquid in the

well above the supplying strata is displaced by a liquid not contaminated with the coloring matter so that there is no more coloring matter in the discharged liquid, a bailer is lowered to take samples at gradually increasing depths, and by discharging the bailer on the surface it can be seen if the samples contain any coloring matter. As can be seen from Fig. 1, when a point below the stratum 14 is reached with the bailer, 70 the bailer will contain a sample of the coloring matter within, thus locating the position of a stratum, the depth being known from the length of the cable and the bailer. If there should be a flow of liquid from the bottom of the well, the coloring matter shown in the bottom of Fig. 1 would be carried away when bailing from the natural level of the well, and consequently if coloring matter should not be found when locating or bailing for samples, it would indicate 80 that the leak is coming from the bottom of the well. To determine if there is another liquid stratum above the liquid stratum 14, the casing 15 must be raised sufficiently high 85 to permit the construction of a bridge or plug above the stratum 14 in the ground formation of the strata 13 and 14, and again, by a similar method it can be determined if any liquid is coming from under said bridge 90 and also the position of the stratum 13. The character of the stratum can be determined by the method explained in my pending application and consisting in using such coloring matter that will give only a particular color with a liquid supposed to be in the well or which can be detected by a chemical or special analysis.

95 In Fig. 2 a different method is shown for the determination of the depth of a liquid stratum, in which case, after the container A is lowered with the coloring matter and the coloring matter diffused in the desired place, the container is raised from the well and water is pumped from the top into the well. 105 The coloring matter above the stratum is forced to diffuse into the stratum, and due to the quantity of liquid in the same, it will be lost while the coloring matter in suspension below the lowest stratum will remain in 110 the well, and by lowering the bailer and extracting samples, the exact location of the lower liquid stratum can be determined, as 115 can be easily seen.

120 Fig. 3 shows a leakage in a casing which can be determined by either one of the two above described methods.

Having thus described my invention, I claim as new and desire to secure by Letters Patent:—

125 1. The method of ascertaining the location at which liquid flows into a well consisting in diffusing coloring matter in the well within the space where the flow of the liquid may be expected, then substituting a 130

liquid not contaminated with said coloring matter in the well, and then getting samples of liquid from different known depths of the space in the well where the said coloring matter was diffused, and ascertaining if the extracted samples contain said coloring matter.

2. The method of ascertaining the location at which the liquid flows into the well, 10 consisting in diffusing coloring matter in the well within the space where the inflow of the liquid may be expected, then tending to displace the colored liquid in the well by pumping or bailing; and then getting samples of liquid from different known depths of the space in the well where the said coloring matter was diffused, and ascertaining if the extracted samples contain said coloring matter.
- 15 3. The method of ascertaining the loca-

tion at which liquid flows into a well, consisting in diffusing coloring matter in the well within the space where the inflow of the liquid may be expected, then pumping or bailing the liquid from the natural level 25 of the well so as to remove the coloring matter lying in the path of the inflowing liquid, and then getting samples of liquid from different known depths of the space in the well where the said coloring matter was diffused, 30 and ascertaining if the extracted samples contain said coloring matter.

In testimony whereof I have signed my name to this specification in the presence of two subscribing witnesses.

TITUS ANDREW BEECHER.
